UNITED STATES PATENT OFFICE.

THOMAS B. JEFFERY, OF CHICAGO, ILLINOIS.

LANTERN-HANGER FOR BICYCLES.

SPECIFICATION forming part of Letters Patent No. 352,191, dated November 9, 1886.

Application filed April 17, 1886. Serial No. 199,221. (No model.)

To all whom it may concern:

Be it known that I, THOMAS B. JEFFERY, a citizen of the United States, residing at Chicago, in the county of Cook and State of Illinois, have invented certain new and useful Improvements in Lantern - Hangers for Bicycles, which is fully set forth in the following specification, reference being had to the accompanying drawings, forming a part thereof,

10 wherein—

Figure 1 is a perspective of the entire hanger. Fig. 2 is a sectional side elevation of the lantern and hanger, the latter being cut at the vertical plane indicated by the dotted line α α , Fig. 3, which is a front elevation of the lamp and hanger in position on the axle, the hubs of the wheel also appearing as stops for the hanger. Fig. 4 is a perspective of a modified form of my improved hanger.

20 A is a bracket secured fast to the top of the lantern B, so that its vertical lip A' may be considered as a flange or lug on the top of the lantern.

25 C' C² are slides or sliding brackets, whose horizontal branches C¹⁰ C²⁰ are slotted at c¹⁰ c²⁰, and stand side by side, their said slots coinciding laterally, so that the clamp-screw D is passed through both and screwed into the vertical lip A' of the bracket A. Each of said 30 horizontal branches C¹⁰ C²⁰ is provided at the end with a tongue or lug, c¹¹ c²¹, protruding into the slot of the other slide, so that, regardless of the fact that said slides may rest their lower edges upon the surface of the horizontal plate A² of the bracket A, they are held in line together for the entire distance between their said lug-bearing ends, and this distance is sufficient to cause them to be rigid as one as respects any strain tending to change their 35 angle to each other in the plane of their faces which are in contact. Said slides have also the vertical branches C¹¹ C²¹ at the ends opposite those having the tongues c¹¹ c²¹, respectively, and said vertical branches terminate at their 40 upper ends in the overhanging hooks C¹² C²², which are interiorly provided with the packing or cushions c¹² c²². The hooks C¹² C²² are designed as bearings for the lantern upon the axle E of the bicycle, between the hubs F F,

45 and the clamp-screw D being loosened the slides C' C² are moved outward until the hooks C¹² C²²

bear against the inner ends of the hubs, and thereupon, the clamp-screw being tightened, the lantern suspended by the hooks cannot move sidewise from the position to which it is thus adjusted. The lantern having this form of hanger is thereby adapted to wheels having wide range of distances between the hubs, being adjustable from the length of one of the slides to nearly the length of both.

50 To prevent the hanger becoming unhooked from the axle by accident, an under hook or bearing, G, is provided, having a cushion, g, on its upper concave surface and vertically adjustable toward and from the line of the overhanging hooks C¹⁰ C²⁰—i. e., toward and from the axle when the hanger is in place thereon. A convenient method of securing this under hook or bearing so that it may be adjusted is that shown in Fig. 4. A vertical slot, h, is made in the vertical lip A' of the bracket A, and the hook G is given a threaded terminal, g', to pass through the slot h, leaving shoulders g² g² to bear against the lip A'. A clamp-nut, H, fitted to the threaded terminal g', 75 secures the hook G at any desired height within the range of the slot h. Two of these under hooks, G, may be used, as seen in Fig. 1, and in that case, preferably, they are clamped upon the vertical arms C¹¹ C²¹ of the slides, said arms having then the slots h' h', corresponding precisely to the slot h in the lip A' of the bracket. The hooks G and their clamp-nuts H are made precisely alike in the two cases. The adjustable under hook or hooks, G, not 80 only serve as a gate to be opened to admit the axle under the hooks C' C², but also serve to adjust the hanger to axles of different diameters, since it is found desirable that the hanger should fit the axle as snugly as possible without being in danger of being revolved with it.

90 I claim—

1. In combination, substantially as set forth, the bracket A, provided with a clamp-screw, the slides having each a horizontal arm slotted to slide on the clamp-screw, and having extensions upward at their remote ends provided with bearings to receive the axle, whereby said slides, being laterally adjustable, are laterally stopped by the hub-shoulders.

95 2. In combination, substantially as set forth, the bracket having the vertical flange pro-

vided with a clamp-screw, the slides having each a vertical arm hooked at the upper end to engage the axle, and a horizontal arm slotted to slide on the clamp-screw, each of said horizontal arms having a projection entering the slot of the other slide.

3. In combination, substantially as set forth, the bracket having the vertical flange provided at the lower part with the clamp-screw, and above said screw having the vertical slot, the slotted slides guided and clamped by the

clamp-screw and having their vertical arms hooked at the upper end, and the lower bearing or bracket adjustable in the slot.

In testimony whereof I have hereunto set my hand, in the presence of two witnesses, at Chicago, Illinois, this 10th day of April, 1886.

THOS. B. JEFFERY.
